UNITED STATES PATENT OFFICE.

AUGUSTINE DAVIS, OF JAMAICA, NEW YORK, ASSIGNOR, BY MESNE ASSIGNMENTS,
TO DAVIS AUTOMATIC EQUIPMENT CORPORATION, OF NEW YORK, N. Y., A CORPO-
RATION OF NEW YORK.

COIN-CONTROLLED MECHANISM.

Application filed July 17, 1920. Serial No. 396,892.

To all whom it may concern:

Be it known that I, AUGUSTINE DAVIS, a citizen of the United States, and a resident of Jamaica, Long Island, in the county of 5 Queens, and city and State of New York, have invented a certain new and useful Improvement in Coin-Controlled Mechanism, of which the following is a specification.

10 The invention is an improvement in coin-controlled mechanism, more especially coin-controlled locks, and has to do with a construction in which a member or detent is displaced by the projecting edge of a coin 15 carried flatwise by a rotary coin-mover. The object of the invention is to insure against coins, particularly when thin, becoming wedged between the cooperating parts, and to avoid wear upon the edges thereof, 20 which in time would tend to cause such result. To this end the cooperating coin-contacting regions are concaved or undercut so that when thrust is exerted through the 25 coin its edges are always opposed by solid metal and drawn away from the sides of the contacts.

In the accompanying drawings forming a part hereof:

Fig. 1 is a rear elevation of the lock, in 30 the unlocked condition, with the cover of the coin-disk casing removed, and showing a coin in position to displace the detent;

Fig. 2 is a fragmentary view, corresponding to Fig. 1, with the cover in place; and 35

Fig. 3 is an enlarged section on the line 3-3 of Fig. 2.

The particular coin-controlled lock mechanism in which the invention is shown embodied is the invention of another, and is 40 not claimed per se herein. Briefly described, a pivoted bolt 8 is urged by a spring 17, and is normally restrained by a pivoted detent, having a spring 24. The arm 26 of the detent extends into proximity 45 to the periphery of a rotary coin-disk 30, whereon the coin is held flat, that is to say, in a plane perpendicular to the axis of rotation. Said disk rotates within a cup 35 having a detachable cover 41, the cup and 50 cover together forming a casing, which is peripherally open at the proper regions for entrance and exit of the coin and the co-operation therewith of the detent. The disk is turned by a knob (not shown) on the

front of the plate 1, and receives the coin 55 from a coin-drop or chute 29 at one side of the arm 26. The detent is disengaged from the spring bolt by the thrust of a coin *a* carried by the disk, retraction of the bolt being effected by a key, through a key 60 cylinder 4 and bit 14.

The contact extremity 27 of the detent arm 26 is formed to pass between side guides 40 and 41^b, of which the member 40, in the particular construction illustrated, is formed 65 by an outturned marginal flange on the cup 35, while the other guide is constituted by the marginal region of the cover, said cover region preferably having a rib or narrow bearing 41^a pressed in therefrom to 70 cooperate with the side of the displaceable coin contact element 27.

Approximately one half 32 of the face of the disk is elevated and the other half depressed, by an amount preferably slightly 75 greater than the thickness of the intended coin; and the intervening shoulder is in-curved or recessed at one side of the center, as shown at 61, to form the back of a coin 80 pocket 31. It is this shoulder which carries the coin forward and exerts thrust upon one portion of its edge, causing another portion of such edge to thrust against the extremity 27 of the member to be actuated, in this instance the detent. The disk and 85 pocket are of such proportions that the edge of the coin projects beyond the periphery of the disk, between the side guides 40 and 41^b. The mechanism is simple and positive in operation, but would be capable of being 90 seriously deranged should the forward edge of the coin be driven past the side of the extremity 27, between the same and one of the side guides, or if its rear edge should escape from the shoulder 61 and wedge between the disk and the cover. This might occur in the case of a thin coin, or as the 95 result of wear in the parts. In a mechanism of this character it is desirable to have the clearances fairly free, and due to ordinary variations in manufacture they will be somewhat greater in some cases than in others; but even if substantial accuracy were observed the possibility of faulty operation 100 would not be entirely removed.

The purpose of the invention is to guard against this danger in a simple and effective manner. The improvement comprises pri- 105

marily the formation of the end face 62 of the extremity 27, which as shown is transversely hollowed, so that the coacting edge of the coin is centralized. Thus, the pressure is never upon the extreme sides or lateral edges of the member, so that wear cannot occur at these regions to develop a wedging entrance for the coin between the member and one or other of the side guides. 10 Secondly, the shoulder 61, where it bears upon the coin, is undercut as seen particularly in Fig. 3, on a curve or inclination, so that the forward pressure on the coin when the resistance of the detent member 15 is encountered causes this portion of the coin edge to hug the depressed face of the disk. By these means relative edgewise dis-

placement of the coin at either region is prevented; and it also becomes possible to allow more width in the coin passage around the axis of the disk, so that the mechanism is safeguarded against choking by both bent and thin coins or pieces. 20

What I claim as new is:

In coin-controlled mechanism, and in combination with a member to be actuated, a rotary coin-mover adapted to move the projecting edge of a coin adjacent said member comprising a disk having an eccentric coin pocket upon its face, formed by a shoulder 25 between high and low regions of the face, said shoulder being beveled undercut to draw the coin to the face of the disk. 30

AUGUSTINE DAVIS.
